United States Patent Office

Des. 209,448
Patented Dec. 5, 1967

209,448

DATA PROCESSING CONSOLE

Walter S. McCormick, Jr., Poughkeepsie, William S. Sheppley, Jr., Rinebeck, and Joseph F. Taterico, Poughkeepsie, N.Y., assignors to International Business Machines Corporation, Armonk, N.Y., a corporation of New York

Filed Nov. 14, 1966, Ser. No. 4,631

Term of patent 14 years

(Cl. D26—5)

FIG. 1

FIG. 2

FIG. 3

FIG. 4

FIG. 5

FIG. 1 is a perspective view of a data processing console embodying our new design;

FIG. 2 is a top plan view;

FIG. 3 is a front elevational view, the opposite sides of the plain end cabinet and of the display cabinet being the same as the sides shown;

FIG. 4 is a side elevational view; and

FIG. 5 is a rear elevational view.

We claim:

The ornamental design for a data processing console, as shown and described.
